DESIGN FOR A MATCH HOLDER

Mary J. Reese, Pittsburg, Kans.

Application June 24, 1938, Serial No. 78,042

Term of patent 14 years

To all whom it may concern:

Be it known that I, Mary J. Reese, a citizen of the United States of America, residing at Pittsburg, county of Crawford, and State of Kansas, have invented a new, original, and ornamental Design for a Match Holder, of which the following is a specification, reference being had to the accompanying drawing, forming part thereof wherein the figure is a perspective view of a match holder, showing my new design.

The opposite side of the design is substantially plain.

I claim:

The ornamental design for a match holder, as shown and described.

MARY J. REESE.
